LOUIS SCHWITZER AND CARL J. WINKLER, OF INDIANAPOLIS, INDIANA, ASSIGNEES
TO SCHWITZER-CUMMINS COMPANY, OF INDIANAPOLIS, INDIANA, A CORPORA-
TION

WATER PUMP

Application filed November 11, 1929. Serial No. 406,238.

This invention relates to a water pump and particularly a centrifugal type of pump used in the water cooling system of internal combustion engines, although the invention 5 is not necessarily limited thereto.

The typical centrifugal pump, as is well known, is provided with an impeller having a plurality of blades caused to rotate upon a shaft within a housing, the water being 10 drawn into the impeller blades laterally and centrally thereof, whereupon the direction of the flow of water is changed to a peripheral flow both by the centrifugal action and the peripheral velocity of the water in the 15 pump.

The purpose of this invention is to provide a more efficient type of pump of this general character which will have the advantages of the centrifugal type of pump while at the 20 same time greatly increasing the efficiency thereof and particularly the quantity and velocity of the water pumped thereby through a circulating system.

One feature of the invention resides in the 25 arrangement of the water intake with respect to an impeller and the outlet. This invention contemplates a peripheral intake as distinguished from the usual lateral intake, as well as a peripheral outlet, the course 30 or flow of the water being slightly angular, directed into the impeller adjacent the periphery thereof and continuing its peripheral travel about the housing and out from the periphery thereof.

35 As will be noted, the inlet is in the periphery of the housing to one side of the impeller and outlet, and the water passage formed in the housing is such as to cause the water to spiral about the periphery thereof 40 into the plane of the impeller and outlet.

By means of this arrangement there is a 45 peripheral flow of water of a spiral character as distinguished from the usual centrifugal flow of an angular character. In other words, there is no angular change in the direction of flow as in the usual type of centrifugal pump. Herein the water enters in the direction of travel of the impeller as distinguished from entering at right angles thereto. Furthermore, it enables the water

to be discharged tangentially from the end of the impeller blades which increases the velocity thereof directly with the increase in velocity of rotation of the impeller. Thus, the flow corresponds directly to the speed of 55 the impeller.

Another advantage of the invention resides in the use of a larger impeller for the same size housing than in the usual centrifugal type of pump, and inasmuch as the velocity 60 of the water is directly responsive to the speed of the ends of the impeller blades, the larger size impeller capable of being used increases the velocity due to the increased diameter thereof. 65

The full nature of the invention will be more clearly understood from the accompanying drawings and the following description and claim:

Fig. 1 is a central vertical section through 70 the pump with the impeller and cover plate mounted thereon. Fig. 2 is an internal view of the pump housing with the impeller removed. Fig. 3 is a section taken on the line 3—3 of Fig. 2. Fig. 4 is a reduced section 75 taken on the line 4—4 of Fig. 1.

In the drawings there is shown in section 80 a pump having a supporting bracket 10 formed integral with a cover plate 11 adapted to be rigidly secured to the pump housing 12. The pump is driven by the usual means not shown herein through the drive shaft 13 and is supported in suitable bushings 14 in the cover plate, and 15 in the pump housing. The usual packing 16 is provided for preventing 85 leakage along the shaft. Rigidly secured upon the shaft there is an impeller 17 provided with radially extending blades 18 adapted to rotate freely within the main annular chamber 19 of the pump housing. 90

The water inlet 20 communicates with the periphery of the spiral chamber 21 formed with a spirally disposed peripheral passage within the pump housing adjacent to but at one side of the main chamber 19; or if desired, 95 double inlets may be employed, one on each side of the main chamber. The outlet 22 communicates directly with the periphery of the main chamber 19 in the same plane thereof. 100

As best illustrated in Figs. 2 and 3, the water passes from the inlet 20 into the spiral chamber 21 to one side of the plane of rotation of the impeller. Inasmuch as the inlet is tangential, the velocity of the water causes it to flow about the peripheral wall thereof. By reason of the formation of the outer wall of the chamber 21 with a shoulder 23, in conjunction with the inwardly extending peripheral fin 24 partially separating the two chambers, the peripheral flow of water is directed toward the periphery of the main chamber and in engagement with the outer ends of the vanes 19 of the impeller which caused its peripheral flow to be continued about the peripheral wall of the main chamber until it escapes through the outlet 22 communicating therewith.

From the foregoing it will be noted that the flow of the water is generally maintained in a peripheral direction and no right angle change of direction occurs. The flow is caused by engagement only with the more swiftly moving peripheral ends of the impeller as distinguished from entering the impeller through the center thereof, which increases the velocity of the water moving from the inlet to the outlet. Thus, resistance to the flow is minimized and the velocity is directly responsive to the speed of the ends of the impeller blades which is increased directly with the increase of the diameter thereof, and the diameter of the impeller being limited only by the internal diameter of the pump housing.

The invention claimed is:

A pump of the character described having a housing forming a main chamber, an outlet conduit communicating therewith, an impeller rotatably mounted in said chamber, an intake chamber formed at one side thereof, a peripheral fin extending inwardly from said housing partially separating said chambers, said intake chamber being provided with a sloping outer wall terminating in said fin for forming in conjunction therewith a substantially spiral passage communicating with said main chamber.

In witness whereof, we have hereunto affixed our signatures.

LOUIS SCHWITZER.
CARL J. WINKLER.
